UNITED STATES PATENT OFFICE.

HERBERT R. YOUNG, OF LAKEPORT, NEW HAMPSHIRE.

DEVICE FOR HOUSE-WIRING.

SPECIFICATION forming part of Letters Patent No. 579,213, dated March 23, 1897.

Application filed January 31, 1896. Serial No. 577,612. (No model.)

To all whom it may concern:

Be it known that I, HERBERT R. YOUNG, a citizen of the United States, residing at Lakeport, in the county of Belknap and State of New Hampshire, have invented certain new and useful Improvements in Devices for House-Wiring; and I do hereby declare the following to be a full, clear, and exact description of the invention, such as will enable others skilled in the art to which it appertains to make and use the same.

This invention relates to certain new and useful improvements in devices for house-wiring; and it has for its objects, primarily, to dispense with the hook on the fishing-wire heretofore employed for running wires out of sight. It is adapted to be applied to the end of the fishing-wire in any suitable manner and is adapted for use in connection with a piece of chain known in electric wiring as the "jack-chain." The body of the device is made of steel and is magnetized and is provided at the end with a plurality of hooks pointing in different directions. When the body of the instrument comes in contact with the chain, it immediately attracts it, and when it is pulled along the chain slides down the tapered end and engages one of the hooks. The body of the instrument is made the same diameter as the hooks, so they will not catch on any obstruction that may be in the path.

Other objects and advantages of the invention will hereinafter appear, and the novel features thereof will be particularly pointed out in the appended claims.

The invention is clearly illustrated in the accompanying drawings, which, with the letters of reference marked thereon, form a part of this specification, and in which—
Figure 1 is a detail in vertical section showing the application of the invention. Fig. 2 is a side elevation of my improved instrument. Fig. 3 is a vertical section through the same. Fig. 4 is an end view.

Referring now to the details of the drawings by letter, A designates the body of the device, which is made of steel and is magnetized. One end is tapered, as shown at a, and at said end are a plurality of hooks extending in different directions therefrom, the body of the instrument being of the same or greater diameter than the hooks, so that the

latter may not catch on any obstruction that may be in their path.

It will be understood that the invention is to be employed for drawing the wires or other material through the conduit or other place where the device is employed.

In practice the device is designed to be attached to the end of the fishing-wire in any suitable manner, in this instance being shown as having a screw-threaded socket A', with which the wire of a threaded portion thereon may be engaged.

Fig. 1 represents a section through the walls and flooring of a building and the manner of running the wires through the same by the aid of the instrument forming the subject-matter of this application. Suppose it to be desired to run a wire down inside a partition, as from a' to b'. The first thing to be done would be to bore a small hole through the partition at a', drop the chain, with the string attached, through the same, and by listening at b' when the chain is dropped it can be very nearly located. Then the second hole is bored at b', and the instrument, attached to a wire, is inserted through this hole and is moved about until it engages and catches the chain, when it is pulled out with the chain, it being understood that a wire is fastened to the string at the upper end, as at the point a', and by means thereof is pulled down through the space in the partition and out at b'.

In Fig. 1, E represents the chain, and A the device forming the subject-matter of this application. The magnet attracts the chain, and the hooks secure it, as set forth. In a similar manner wires may be run through under floors, as indicated at the top and bottom of the sketch.

As the device comes in contact with the chain, being magnetized, the chain is immediately attracted thereto, and as it is pulled along the chain slides down the tapered end and engages in one of the hooks.

The simplicity and advantages of the devices herein described will be readily appreciated by those having occasion to use such class of devices.

It is almost impossible for the instrument to touch the chain without catching it on one or the other of the hooks.

Modifications in details may be resorted to

without departing from the spirit of the invention or sacrificing any of its advantages.

Having thus described the invention, what is claimed as new is—

- 5 1. A magnetized body having provision for attachment to a fishing-wire and magnetized and provided at one end with a plurality of hooks, substantially as described.
- 10 2. A magnetized body having provision for attachment to a fishing-wire and magnetized and provided at one end with a plurality of hooks, the body portion being tapered at such end, substantially as described.
- 15 3. An electrician's implement for running wires, comprising a magnetized body portion

having a tapered end and a plurality of hooks at said end, substantially as described.

4. An electrician's implement for running wires, comprising a magnetized body portion having a tapered end and a plurality of hooks 20 at said end, and a screw-threaded socket at the other end, substantially as described.

In testimony whereof I have signed this specification in the presence of two subscribing witnesses.

HERBERT R. YOUNG.
